UNITED STATES PATENT OFFICE.

DAVID LIPPY, OF MANSFIELD, OHIO, ASSIGNOR OF FOUR-FIFTHS TO LORENZO D. PATTEN, GEORGE MOOREHOUSE, JAMES T. SAWHILL, AND GEORGE W. STATLER, OF MANSFIELD, OHIO.

PUMP.

SPECIFICATION forming part of Letters Patent No. 689,552, dated December 24, 1901.

Application filed June 15, 1901. Serial No. 64,655. (No model.)

To all whom it may concern:

Be it known that I, DAVID LIPPY, a citizen of the United States, residing at Mansfield, in the county of Richland and State of Ohio, have invented certain new and useful Improvements in Pumps; and I do hereby declare that the following is a full, clear, and exact description of the same, reference being had to the annexed drawings, making a part 10 of this specification, and to the figures of reference marked thereon, in which—

Figure 1 is a side elevation showing the pump properly connected for power use. Fig. 15 2 is a side elevation showing the pump properly connected for hand use.

The present invention has relation to pumps designed for either hand or power use; and it consists in the novel construction hereinafter described, and particularly pointed out in 20 in the claims.

Similar numerals of reference indicate corresponding parts in both figures of the drawings.

In the accompanying drawings, 1 represents 25 the stock, to which is connected in the usual manner the well tube or casing, and into which well tube or casing is extended through the stock the reciprocating rod 2, said reciprocating rod being provided with the ordinary piston and valve. To the top or upper end of the stock 1 is secured the head 3, which is substantially of the form shown and is for the purpose of providing a means for connecting the working parts of the pump. To the head 30 3 is pivotally connected the link or connecting-bar 4, which link or connecting-bar extends upward and has pivotally connected to its upper end the head 5, to which head 5 is connected the operating-lever 6. To one side 40 of the head 5 is connected or formed integral with said head the arm 7, which arm is spaced or set a short distance from the operating-lever 6, so as to provide room for the adjustable weight 8. To the head 5 is pivotally connected the clutch-bar 9, which clutch-bar is 45 for the purpose of gripping the reciprocating rod 2. In the drawings I have illustrated the clutch-bar held in proper position upon the reciprocating rod 2 by means of a set-screw

10; but it will be understood that any other well-known means may be employed without departing from the nature of my invention. The weight 8 is adjustably connected to the arm 7, said arm being set to one side of the operating-handle 6, so as to bring the weight 50 out of the way of the operating-handle 6; but it will be understood that it is immaterial so far as the operation of the pump is concerned whether the weight 8 is located upon the arm 7 or the lever 6.

The object and purpose of adjustably connecting the weight 8 either to the arm 7 or to the operating-handle 6 is to place said weight into such a position in reference to the fulcrum-point of the operating-handle 6 as to 55 compensate for different weights of columns of water to be lifted, and thereby provide a perfect counterbalance, reference being had to the weight of the reciprocating rod and the weight to be lifted by said reciprocating rod. 60

It will be understood that in the operation of pumps it is frequently desirable to operate the pump either by hand or wind or other power, and in order to provide a single pump capable of operation either by hand or power 75 I provide the downward-extending rod 11, which downward-extending rod is pivotally connected to the socket-head 5 at a common center with the clutch-bar 9, said downward-extending rod being pivotally connected at 80 its bottom or lower end to the lever 12, which lever is pivotally connected or fulcrumed to a bracket, such as 13, or its equivalent. Upon the lever 12 is adjustably connected the weight 8, which weight is for the same purpose when 85 placed upon the lever 12 that it is when placed upon the operating-handle 6 or arm 7 and is to be adjusted in the same manner, reference being had to the increased leverage of the lever 12 over that of the operating-handle 6 and 90 the weight to be lifted with the power used.

For the purpose of adjustment for the connection between the socket-head 5 and the lever 12 the downward-extending rod 11 is provided with a series of apertures 14, said 95 apertures being located at the top or upper end of the downward-extending rod 11.

For the purpose of providing a means for

connecting power of any kind to the reciprocating rod 2 the yoke 15 is provided, said yoke being pivotally attached in the usual manner.

It will be understood that by my peculiar arrangement I am enabled to so adjust the weight either upon the lever, arm, or operating-handle that the elevating of water or other liquids can be accomplished with ease by reason of the weight acting as a counterbalance, 10 overcoming the resistance of the column or weight of water or other liquid to be lifted plus the small power required to operate the pump in connection with the adjustable weight either by hand or other power, the 15 difference required in power being only such as the difference between the force exerted by weight and the resistance offered by the column of water or other liquid to be lifted.

The purpose of placing the arm 7 at one 20 side of the operating-lever 6 is to bring the weight 8 out of the way of the hand of the operator.

Having fully described my invention, what I claim as new, and desire to secure by Letters 25 Patent, is—

1. In a pump, a stock and a casing therefor, a reciprocating rod, a frame fixed to the

stock, a socket supported by the frame carried by the stock, an operating-handle fixed to the socket, and an arm located at one side 30 of the operating-handle, and an adjustable weight located upon the arm located at one side of the operating-handle and adjustable to and from the reciprocating rod, and a clutch connected to the reciprocating rod, substantially as and for the purpose specified. 35

2. The combination of a stock, a head connected thereto, a reciprocating rod and a clutch-bar connected to said reciprocating rod, a socket-head pivotally connected to a 40 link or connecting-bar supported by the head, a downward-extending arm pivoted at a common center with the pivotal joint of the clutch-bar at its upper end, and the lower end thereof pivoted to a lever and said lever provided 45 with an adjustable weight, substantially as and for the purpose specified.

In testimony that I claim the above I have hereunto subscribed my name in the presence of two witnesses.

DAVID LIPPY.
